UNITED STATES PATENT OFFICE.

WILLIAM J. GODTEL, OF CULBERTSON, NEBRASKA.

SUGAR-BEET LIFTER AND TOPPER.

Application filed June 15, 1923. Serial No. 645,608.

This invention relates to improvements in beet topers and has for its primary object to provide a device of this character which can be used with any type of beet digger.

5 A further object of the invention is to provide a beet topper having novel means for lifting the beets to the topping knives.

A still further object of the invention is to provide a beet lifter and topper of the 10 character indicated having a novel means for driving the beet lifter and for disengaging the lifter from the beets for the purpose of loading or discharging the topped beets onto the ground or on conveyor.

15 A still further object of the invention is to provide novel means whereby the beets are grasped and capsized.

And a still further object of the invention is to provide a machine of the above 20 indicated character, which is simple in construction, durable, efficient for the purpose intended, and one that can be manufactured at a very low cost.

These and like objects of the invention will 25 be better understood as the description follows and as is specifically pointed out in the appended claims.

Referring to the accompanying drawings which form a part of this specification,

30 Figure 1 is a top plan view of a beet lifter and topper constructed in accordance with my invention.

Figure 2 is a side elevation of same.

Figure 3 is a section taken on line 3—3 35 of Figure 2.

Figure 4 is an enlarged sectional view taken on line 4—4 of Figure 2.

Figure 5 is an enlarged detailed view of a portion of the beet lifter.

40 Figure 6 is a top plan view of same, and Figure 7 is an enlarged side elevation, partly in section, of the beet lifter driving means.

Referring to the accompanying drawings 45 in detail, like characters will be used to designate like parts in the different views.

In the drawings, the numeral 1 indicates a frame which is rectangular and has an axle 2 journaled therein, on the free ends of 50 which are mounted drive wheels 3.

Mounted within the rectangular frame 1 and supported in spaced relation by braces 4 are a pair of oval shaped frames 5 disposed in vertical planes. At spaced intervals 55 for the greater part of their circumferences at one end thereof, each of the oval

shaped frames 5 is provided with horizontal bores in which are mounted sleeves 6 to act as bearings for shafts 7. One end of each shaft 7 is forked, as at 8, and the forked ends are reduced for receiving thereon oppositely disposed grooved pulleys 9, all of which is clearly shown in Figure 4 of the accompanying drawings.

A beet lifter comprising a pair of chains 65 9' composed of a series of links 10 hingedly connected together, as at 11, is adapted to be supported between the oppositely disposed pulleys 9, as is clearly shown in Figure 4, and each link is provided with a beet engaging member 12 in the form of a prong or spike. The points of the prongs on one lifter chain 9' are adapted to point towards the points of the prongs on the other lifter chain 9' for engaging the beets therebe- 70 tween.

A shaft 13 is mounted longitudinally of the frame 1 and supported at its forward end by a cross brace 14 and at its rear end by a vertical brace 15, which is in turn supported by braces 16 running to the rectangular frame 1. A pair of flanged wheels 17 is provided, one being positioned within the rear end of each of the oval shaped frames 5, and each mounted on a shaft 18, one end 80 of each shaft being supported in a vertical brace or standard 15, while the opposite ends of the shafts 18 are mounted in suitable supports 18' extending from opposite sides of the oval shaped frames 5. Each of the 85 flanged wheels 17 receives therein a beet lifting chain 9', and the flanges of the wheels 17 at the inner side thereof are provided with spaced notches 20 for receiving therein the prongs 12 of the chains 9'. A 90 beveled gear 21 is mounted on the front end of the shaft 13 and meshes with a beveled gear 21' keyed to the shaft 2, while a beveled gear 22 is keyed to the shaft 13 adjacent its rear end and meshes with a beveled gear 23 95 on one of the shafts 18, while the wheel 17 on the opposite side of the machine is driven through suitable gearing 24, 25, and 26, the gear 25 being mounted on a bracket 25' carried by one of the supports 18'.

A pair of disk knives 27 is mounted on supports 28 and each of the disks has a shaft 29 that is provided at its lower end with a bevel-gear 30 adapted to mesh with a bevel-gear 31 on the shaft 2 for rotating said 100 knives.

In the operation of my improved beet

lifter and topper, it will be assumed that any suitable digger is employed, which elevates the beets to the point indicated by the numeral 32, at which point the prongs 12 engage the beets from opposite sides and through rotation of the wheels 17 which receive their motion from the shaft 13, the lifter chains 9' are revolved until the beets are capsized and brought directly above the revolving disk knives 27, at which time the tops are cut from the beets, said tops falling, at the point 35, onto the ground or a conveyor. The beets continue to travel towards the rear of the machine until the point 33 is reached, where the chains 9' diverge and allow the beets to drop to the ground or onto a conveyor, (not shown).

In view of the foregoing description of my invention taken in connection with the accompanying drawings, it is thought that any further explanation as to the construction, operation, and objects of same is unnecessary.

While I have shown and described the preferred form of my invention, I realize that various minor changes may be resorted to, without departing from the spirit and scope of the invention as claimed, and therefore, I do not wish to limit myself to the exact details of construction shown, nor to the combination and arrangement of parts.

What I claim as new and desire to secure by Letters Patent is:

1. A beet lifter and topper comprising a wheeled frame, a pair of oval shaped auxiliary frames carried by said wheeled frame and spaced apart in parallel vertical planes, a series of grooved pulleys rotatably mounted in each of said oval shaped auxiliary frames and arranged in pairs, spaced chains mounted for movement between the grooved pulleys, topping knives supported from the wheeled frame, and means for operating

the chains and topping knives from the supporting wheels of the main frame. 45

2. A beet lifter and topper comprising a wheeled frame, a pair of auxiliary frames carried thereby, a series of grooved pulleys rotatably mounted in each of said auxiliary frames and arranged in pairs, spaced chains 50 mounted for movement between the pairs of pulleys, prongs projecting from the links of the chains with those on one chain projecting towards those on the other, a pair of flanged wheels journaled in said auxiliary frames and over which the chains extend, said wheels having notches in the periphery of the inner flange thereof through which the prongs extend, topping knives journaled between said auxiliary frames, and means 55 operating the flanged wheels and topping knives from the supporting wheels of the main frame.

3. A beet lifter and topper comprising a wheeled frame, a pair of oval shaped spaced 60 apart vertical auxiliary frames carried by said wheeled frame, a series of grooved pulleys rotatably mounted in each of said auxiliary frames in one end portion thereof, a pair of angularly disposed flanged wheels 70 in the other end portion of said auxiliary frame, said flanged wheels being mounted on horizontal axles for rotary movement and at a greater distance apart than the aforementioned pulleys, a pair of chains passing between the sets of pulleys and companion flanged wheels in each auxiliary frame, means carried by said chains for engaging the beets, topping knives carried by the wheeled frame, and means for rotating the 75 flanged wheels and topping knives from the supporting wheels of the main frame.

In testimony whereof, I have affixed my signature.

WILLIAM J. GODTEL.
